CLAIM

I claim the ornamental design for a tool box with illumination lamp, as shown and described.

DESCRIPTION

FIG. 1 is a frontal perspective view of a tool box with illumination lamp showing my design.

FIG. 2 is a front view thereof;

FIG. 3 is a rear view thereof;

FIG. 4 is a side view thereof;

FIG. 5 is an opposite side view thereof;

FIG. 6 is a plan view thereof;

FIG. 7 is a bottom view thereof; and,

FIG. 8 is a perspective view thereof, in an open position depicting the interior.
